LOUVER CONSTRUCTION

Earl Phillip Jones, Fort Lauderdale, Fla., assignor to Gate City Sash & Door Company, Fort Lauderdale, Fla., a corporation of Florida

Application July 24, 1937, Serial No. 155,391

3 Claims. (Cl. 268—96)

This invention relates to adjustable louvers or shutters for windows, ventilators, or other places where openings are desired for one purpose or another.

Generally stated, the object of the invention is to provide a novel and improved construction and arrangement whereby a manually operated worm gearing, or the equivalent thereof, is advantageously employed in an inexpensive form to manually control the opening and closing movements of the shutters of the louver structure.

It is also an object to provide certain details and features of construction tending to increase the general efficiency and desirability of a louver construction of this particular character.

To the foregoing and other useful ends, the invention consists in matters hereinafter set forth and claimed and shown in the accompanying drawing, in which—

Fig. 1 is a perspective of a manually adjustable louver construction involving the principles of the invention.

Fig. 2 is a fragmentary vertical section on line 2—2 in Fig. 1, on a larger scale.

Fig. 3 is a fragmentary detail sectional view on line 3—3 in Fig. 2 of the drawing.

Figs. 4, 5 and 6 are perspective views of the different parts of the manually operated worm gearing by which the shutters of the louver construction are opened and closed.

As thus illustrated, the invention comprises a series of shutters 1 that each have a stationary pivot 2 at each end thereof, and which each have a movable pivot 3 at each end thereof, said movable pivots being connected to move in unison by a vertically disposed strip or member 4, at each side of the louver construction, the latter being mounted in the window frame 5, or other frame, in the manner shown in the drawing. In this way, by up-and-down movement of the two members 4, the louver shutters 1 are tilted in unison about their stationary pivots 2, previously mentioned.

To facilitate this adjustment of the shutters, and to make it easy and convenient, a worm gearing is provided at one side of the structure, comprising a bracket plate 6 that is fastened by screws 7 to one side of the said frame. This bracket plate is preferably curved or formed with a groove at 8, and is desirably set into a recess 9 in the said frame, as shown more clearly in Fig. 3 of the drawing. Also, it will be seen, the plate 6 has a pair of ears forming bearings 10 that are struck out from the plate, leaving an opening

11 between the two bearings. In addition, the lower end of the plate 6 is provided with an opening 12 for a rivet 13 that forms a pivotal axis for the gear 14 that is rigid with the arm 15, which latter has in turn a bent end portion 16 provided with an opening 17 for a pin or pivot 18 that provides a pivotal connection between the arm 15 and the member 4, previously mentioned. The horizontal shaft 19, in the form of a rod, extends through the frame 5, as shown, and is mounted in the bearings 10 previously mentioned, the groove 8 providing clearance for said rod, and upon this shaft there is fixed a worm 20 for engagement with the gear 14, previously mentioned. The outer end of the shaft 19 is provided with a handle 21, by which the shaft can be manually rotated.

In operation, when the shaft 19 is rotated, in one direction, the worm gearing provided will cause the shutters 1 to move into a direction 20 to provide openings between them, which openings can be greater or less, according to the degree of rotation given the said shaft by the said handle. Then, when it is desired to close the louver construction thus provided, the said shaft 25 and handle can be rotated in the opposite direction, with the result that the louver shutters 1 will be brought into overlapping engagement with each other, thus tightly closing the louver.

It will be seen that, in some cases, it might be desirable to make the members 4 stationary, and to make the members 22, which connect together the pivots 2, movable up and down instead. In such case, the arm 15 would be pivoted on the members 22, instead of on the members 4, and in this way the worm gearing can be applied either as shown, or in a reversed position, so to speak, if desired. But in either case, the general principle and the mode of operation are substantially the same, the only difference being that in the drawing the upper and outer pivots of the shutters are stationary, whereas with the said reverse arrangement, the lower and inner pivots would be stationary instead.

Thus, the invention provides a comparatively simple and inexpensive hardware unit for attachment to the frame or adjustable louver of a shutter construction. The unit may be complete, with all parts thereof permanently connected together, when the unit is complete for use, and it is then only necessary to insert the said screws 7 through the four holes 23 of the bracket plate 6 previously mentioned, in order to fasten the unit in place. Of course, the frame must be bored for the shaft 19, and one method

of assembly of the unit with the louver construction would be as follows: The frame is made with the recess 9, and before the outer facing strip 24 is fastened in place, it may be bored for the shaft 19, and the handle 21 would not be fastened on the outer end of the shaft until after the latter is inserted through the strip 24 and the latter has been fastened in place. The said pivot 18 may be of any suitable character, but it is shown as a wood screw, which can be screwed into the member 4 to the extent that its end will loosely engage the opening 17, previously mentioned. Of course, after the strip 24 has been fastened in place, the handle 21 may then be suitably fastened to the outer end of the shaft, so that it can be used for rotating the latter. In this way, the assembling of the elements is quickly and easily done, but the invention, of course, is not limited to any particular manner of applying or assembling the different elements of the louver construction with the hardware unit shown and described.

It is of the essence of the invention that the construction is such that the worm 20 not only operates to rotate the shutters about their individual axes 3, but also serves to hold the shutters in any angle of adjustment thereof.

It will be seen that the recess 25 is comparatively shallow, and that its open side face toward the other side of the window frame. In addition, it will be seen that the mechanical elements enclosed in this recess are combined and put together in a way that leaves the open side of the recess flush, so that nothing can interfere with the free movement of the member 4, the latter practically sliding up and down and more or less horizontally on the flat surface of the side of the window frame in which the said recess is formed. The said member 4 is disposed snugly between the side of the window frame and the adjacent ends of the shutters, so that the entire shutter construction is compact and easily put together. The bracket plate 6 is fastened by the screws 7 to the closed inner side of the said recess 25, so that this plate and the flat portions 14 and 15 are in vertical planes disposed between the vertical plane of the member 4 and the vertical plane of the closed inner side of the recess. Also, it will be seen that the grooves 8, at opposite sides of the bearings 10, provide clearance for the rod or shaft 19, and that with two grooves the device is either a right or a left, and that it can be used at either the right or the left side of the window. The flat portions 14 and 15 are spaced a distance from the member 4 sufficient to bring the gear wheel 14 into the vertical plane of the axis of the rod or shaft 19, in the manner shown more clearly in Fig. 3 of the drawing. It will be

seen that the opening 11 provides clearance for the worm 20, and that the diameter of the latter is substantially the same as the distance between the member 4 and the closed inner side of the recess in which the worm gear device is mounted. The bearings 10 are formed, it will be seen, by metal that is bent out of the opening 11 in the stamping or forming of the bracket plate. Thus the axis of the rod or shaft 19 is in a vertical plane between the vertical plane of the member 4 and the vertical plane of the bracket plate.

What I claim as my invention is:

1. In combination with a window frame, with a shallow open recess in one side thereof, facing the opposite other side, shutters pivoted at their ends on the opposite sides of the frame, a vertically disposed flat member pivoted on the end of each shutter, so the end of each shutter has two pivots, one fixed and the other movable about the axis of the fixed pivot, interposed snugly between the ends of the shutters and said recessed side of the frame, a vertically disposed bracket plate secured in said recess, by screws inserted through its lower portion into the closed inner side of said recess, so that said plate is disposed in a vertical plane between said member and the back of said recess, a pivot on the upper end of said plate, a gear wheel on said pivot, rotating in a vertical plane between said member and said plate, a pivot on said member, an arm rigid with said wheel and engaging said last mentioned pivot, bearings on said plate, below said wheel, a horizontal rod in said bearings, so that said rod rotates about an axis at right angles to the axis of said wheel, and a worm on said rod, engaging the lower edge of said gear wheel, so that by rotation of said rod all of the shutters are operated, said plate and wheel and arm and worm being entirely within said recess, so that the open outer side of the latter is flush to permit free movement of said member close thereto, and said wheel being spaced from said member a distance to bring this wheel into the vertical plane of the axis of said worm, with said member presenting one flat side to said recess and the other flat side to the ends of the shutters.

2. A structure as specified in claim 1, said plate having an opening to provide clearance for said worm, and from which opening metal is bent out to form said bearings.

3. A structure as specified in claim 1, said plate having an opening to provide clearance for said worm, and from which opening metal is bent out to form said bearings, said plate having a groove to provide clearance for said rod.

EARL PHILLIP JONES.
